PANTY HOSE SIZING FORM

Robert E. Merritt, Mount Airy, N.C., assignor to Renfro Hosiery Mills Company, Mount Airy, N.C.

Filed Nov. 20, 1969, Ser. No. 20,190

Term of patent 14 years

Int. Cl. D15—08

U.S. Cl. D47—5

FIG. 1 is a rear perspective view of a panty hose sizing form, showing my design;

FIG. 2 is a right side elevational view thereof;

FIG. 3 is a front elevational view thereof; and

FIG. 4 is a cross sectional view taken on line 4—4 of FIG. 2.

I claim:

The ornamental design for a panty hose sizing form, substantially as shown.
